Primary Examiner — Cynthia Underwood(74) *Attorney, Agent, or Firm* — Edward S. Sherman(57) **CLAIM**

The ornamental design for a “vessel with a saddled shaped rim,” as shown and described.

DESCRIPTION

FIG. 1 is a perspective view of the “vessel with a saddled shaped rim”, showing our new design;

FIG. 2 is a top plan view thereof;

FIG. 3 is a front elevation view, the rear elevation view being the mirror image thereof;

FIG. 4 is a right side elevation view, the left side elevation view being the mirror image thereof; and,

FIG. 5 is a bottom plan view thereof.

The region within the broken line in FIG. 5 forms no part of the claimed design.
